UNITED STATES PATENT OFFICE.

PETER H. RAUN, OF FREDERICK, MARYLAND, ASSIGNOR TO THE FREDERICK ENGINEERING COMPANY, OF FREDERICK, MARYLAND, A CORPORATION OF MARYLAND.

APPARATUS FOR HANDLING ASHES AND OTHER MATERIALS.

Application filed January 10, 1923 Serial No. 611,769.

My invention relates to a means for handling ashes and other materials.

Among the objects of my invention are:—

To provide a means for handling ashes and other materials according to which they are first caused to pass through a crusher mechanism which allows all the pieces of material that are of a predetermined size and sizes thereunder to pass and which reduces all the larger pieces to said predetermined size and sizes thereunder, then delivering the detritus formed of said pieces into a trough, pipe or other conductor therefor, then applying a current of fluid to said detritus in such a manner as to prevent the compaction thereof in order to produce a current of fluid with the loose particles of material transported therein, then delivering the agglomerate of fluid and material to a suitable pump having passages larger than said predetermined size, and by use of said pump forcing said agglomerate to a suitable dumping location.

To provide a crusher mechanism for use with my improved ash handling means comprising means for reducing the ashes to a predetermined size and sizes thereunder, including means adapted to yield to prevent materials having a high crushing strength from breaking the parts of my improved crusher.

To provide a trough, pipe or other conductor having a peculiarly formed interior which shall effectually prevent compaction of the material carried thereby and will insure continuous and regular passage of the material therethrough when a current of fluid is applied thereto.

To provide a pump for the circulation of the fluid and combining with the pump a reservoir on its induction side so that there shall be always an effective head upon said side.

These and other objects of my invention will become apparent in the following specification, reference being had to the accompanying drawings, and the novel means by which said objects are effectuated will be definitely pointed out in the claims.

On the accompanying drawings arrows are placed adjacent dotted lines in order to show the direction in which the section indicated by the dotted line is viewed.

In the drawings:—

Fig. 1 is a side elevation showing parts in section of an ash pit of a furnace joining the

crusher gate, the corresponding dumping grate, the chute for the detritus and a section of the trough and showing the crusher mechanism of my invention.

Fig. 2 is a fragmentary cross sectional view of the parts shown in Fig. 1 when viewed in the direction of the arrow 4 in said figure.

Fig. 3 is a side elevation of the crusher when viewed in the direction of the arrow 5 in Fig. 1.

Figs. 4, 5 and 6 are, respectively, sections of the trough which may be used with the crusher of my invention.

Fig. 7 is a section of a special form of trough that may be used if desired, and

Fig. 8 shows a modified arrangement of the crusher gate with respect to the crusher plate.

In the drawings:—

20 is the ash pit of a furnace and the latter may be either fired by hand or by any approved stoker, the grate bars being represented by 21 and the dumping bars by 22, the latter serving to dump the ashes in any approved manner into the ash pit 20.

At the bottom of each ash pit 20 there are shown in the drawings two crusher gate frames 23—23. For an ash pit smaller than that shown in the drawings, but a single crusher gate frame would be secured to the bottom thereof. For a larger ash pit more than two crusher gate frames would be employed.

In the rear side of the frame 23 there is formed a pair of bearings 24—24 in which is revolvably mounted the shaft 25. To the shaft 25 there is secured the crusher 26 having a plurality of curved faces 27, 28 and 29 and with approximately flat faces 30 and 31 between adjacent parts of curved faces.

The curved faces 27 and 29 of differing radii are coaxial with the axis of the shaft 25 and the curved face 28 is eccentrically disposed with reference to said axis. The faces 30 and 31 are preferably radially disposed with reference to the axis of the shaft 25.

The rear of the frame 23 is provided with an opening 32 for the passage therethrough of the crusher 26 and the upper edge of said opening closely approaches the curved surface 29.

The front of the frame 23 is provided with a pair of brackets 33—33 in which are formed bearings for the operating shaft 34. The

- brackets 33 also comprise bearings for the shaft 35 which extends along the front of the furnaces and is provided with a plurality of pinions 36 each of which meshes 5 with a gear 37 fastened upon the shaft 34. Each gear 37 is provided with an eccentrically disposed pin 38 upon which is journaled the connecting rod 39 which passes through the tie plate 40 and is provided with a head 10 41 which slides freely within the U-shaped adjusting member 42. A spring 43 is placed upon the rod 30 between the head 41 and tie plate 40 and the latter is secured to the member 42.
- 15 An arm 44 is secured upon the shaft 25, its outer end being provided with the pin 45 revolvably mounted in the block 46. The block 46 slides freely in the member 42 and its location therein is adjusted by the screw 47.
- 20 The pin 45 is provided with a handle and is threaded into the arm 44 so that the connecting rod 39 may be disconnected from the arm 44 whenever it is desirable to operate the crusher 26 by hand.
- 25 The relief plate 48 is hinged as at 49 to the brackets 33 and it rests against springs such as 50. Screws such as 51 provided with shoulders such as 52 support the springs 50 and serve to adjust the location of the lower portion 30 of the plate 48 with reference to the crusher 26 and the plate 48 is preferably provided with a plurality of serrations 53 trenchant towards the pivot 49.
- The curved surfaces 27, 28 and 29 are preferably corrugated as shown in Fig. 5 for the purpose of reducing the friction.
- When it is desired to operate the crusher 26 by hand for any purpose, as for instance, a breakdown of the driving mechanism that 40 operates it, or when my improved crusher mechanism is used in a plant too small to warrant the use of driving mechanism therefor, then the connecting rod 39 is either disconnected from the arm 44, as before explained, 45 or omitted altogether, then the hand lever 54 is introduced within holes provided in the flanges 55—55 formed upon the arm 44 and used for vibrating the crusher 26.
- Below each crusher gate there is provided 50 a chute such as 56 which receives the detritus from the crusher mechanism and delivers it to the trough 57.
- The trough 57 extends underneath the furnaces whatever number there may be of same 55 and it is provided with a gentle slope and at the highest point of the slope a nozzle may be provided which is connected to a source of water and insures a constant flow thereof within the trough 57. In order to prevent 60 compaction of the detritus within the trough 57 and to increase the life of said trough wherever any part thereof is subject to pressure as for instance, on the bottom where it is subject to the pressure produced by the effect 65 of gravity upon the detritus or upon the outer

curve of curved portions of said trough where said trough is subject to the pressure produced by centrifugal force upon said detritus, the surface subject to pressure is corrugated as shown at 59 in Figs. 1 and 4 which represent sections of a straight portion of trough, and wherever the trough is curved it is provided with the bottom corrugations 59 as shown in Figs. 5 and 6 and with corrugations as at 60 upon the outside curve of the curved 75 portions of said trough.

For certain purposes and in handling certain materials, I find it advisable to corrugate the bottom and sides of the trough as shown in Fig. 7.

The rule to be followed in determining the pitch of said corrugations is that the pitch must not be so great that the large particles will become compacted in the corrugations, nor so small that the small particles will 85 choke the corrugations.

I preferably chill these corrugations and thus greatly increase the life of the trough. Furthermore, the detritus moves much more freely owing to the existence of the corrugations because its friction with them is reduced. That is to say the corrugations are of such size that the fine ash tends to sift to the bottom of the corrugations and the water tends to buoy up the ash or float the same in a layer substantially in alignment with the extremities of the corrugations. The larger ash then tends to ride on the fine ash in its progress through the trough or in other words the big ash has substantially point contact with the extremities of the corrugations thereby passing more freely through the trough by reason of reduction in friction contact.

Another effect that greatly increases the efficiency of my improved trough is that the current of water has a clear space along the bottom of the corrugations which does not become filled with material and, consequently, the water can buoy the detritus and diminish its pressure upon the corrugations. Furthermore, the erosive action of the water passing along the bottom of the corrugations prevents compaction of the detritus.

While I have shown one form of crusher mechanism for use with my improved means for hauling ashes and other materials, it is to be understood that any approved form of crusher mechanism may be used therefor. It is also to be understood that many of the apertures may be changed and that many features of the system may be varied without departing from the spirit of my invention.

One such variation is shown in Fig. 8 in which the crusher mechanism is placed immediately under the stoker grate 21. The parts are arranged similarly to those shown in Fig. 3 excepting that the lever 44^a is provided with an arm 44^b which is connected by the link 44^c with the crusher 26^a. The 130

crusher mechanism frame 23^a which supports the crusher 26^a is secured at the top of the ash pit 20 instead of near the bottom thereof.

I claim:—

- 5 1. In a crusher mechanism, the combination with a frame, of a crusher pivotally mounted therein on an axis off center from the center line of said frame, the operative portion of said crusher comprising a plurality of alternately positioned concentric and eccentric curved surfaces, a plate pivotally mounted in said frame and a spring for yieldably supporting said plate at a predetermined distance from said crusher in cooperative 10 relation to each of said curved surfaces.
- 15 2. In a crusher mechanism, the combination with a frame, of a crusher pivotally mounted therein on an axis off center from the center line of said frame, the operative portion of said crusher comprising independently curved and alternately positioned, concentric and eccentric surfaces, a plate pivotally mounted in said frame and a spring for yieldably supporting said plate at a predetermined 20 distance from said gate, said coaxially aligned surfaces being of different radii than the adjacent unaligned surface.
- 25 3. A crusher mechanism comprising in combination a frame, a crusher member pivotally mounted adjacent one side of said

frame, a spring pressed plate pivotally mounted at the opposite side of said frame, said crusher member being arranged to oscillate toward and away from said spring pressed plate and having a plurality of concentrically and eccentrically independently curved faces of differing radii connected in a plane passing through the pivot thereof each adapted to successively cooperate with biting surfaces on said plate for reducing the size 35 of material passed therebetween.

4. A crusher mechanism comprising a frame, a crusher member pivotally mounted adjacent one side of said frame for oscillating motion, a spring pressed plate pivotally mounted at the opposite side of said frame, said crusher member having a plurality of independent curved surfaces with the extreme end faces of said crusher curved concentrically with respect to the pivot thereof and the intermediate surface of said crusher curved eccentrically with respect to the pivot thereof and joined in substantially radial planes, each of said surfaces successively 45 cooperating with said spring pressed plate for reducing the size of material passing therebetween.

In testimony whereof, I affix my signature.

PETER H. RAUN.
